United States Patent Office.

SIMON F. STANTON, OF MANCHESTER, NEW HAMPSHIRE, AND ORVILLE RIPLEY, OF CHARLESTOWN, MASSACHUSETTS.

Letters Patent No. 94,040, dated August 24, 1869.

IMPROVEMENT IN STEAM-CYLINDER-OILER.

The Schedule referred to in these Letters Patent and making part of the same.

To all whom it may concern:

Be it known that we, SIMON F. STANTON, of Manchester, in the county of Hillsborough, and State of New Hampshire, and ORVILLE RIPLEY, of Charlestown, in the county of Middlesex, and State of Massachusetts, have invented a new and "Improved Oiler for Locomotive-Cylinders;" and we do hereby declare that the following is a full, clear, and exact description thereof, which will enable others skilled in the art to make and use the same, reference being had to the accompanying drawings, forming a part of this specification, in which—

Figure 1 represents a perspective outline view of this invention.

Figure 2 represents a sectional view, showing its working parts.

Figure 3 is a plan or rear view of the piston.

Figure 4 is a view of the front of the same.

Similar letters of reference indicate like parts.

This invention relates to a stationary oiler, surmounting the top of locomotive-engine boilers, near the smoke-stack, having a reservoir and suitable means for conveying the oil from the same to the steam-chests for lubricating the cylinders, without the engineer or fireman leaving their cab for this purpose.

A, fig. 2, represents the reservoir, made of sheet-metal, its seams soldered, or it may be cast of one piece of metal, its inlet closed by a cap, V, and its outlet, A', an open port, communicating with the cylinder B.

B is the cylinder, cast of one piece of metal, having three openings, one at the top, through which the oil passes and enters from the reservoir, the second, which is covered by the cylinder-head W, and serves as a guide for the piston-rod, and the third at its further extremity, which opens into the outlet-chamber, and also forms the seat for the valve H, which closes the same.

C is the perforated piston closed by the valve K, which piston forces the oil out of the cylinder into the outlet-chamber P, and thence into the conducting-pipes.

D is the partitioned tubular piston-rod, which receives, at its forward end, by a screw-thread, the shank of the piston, and through that the valve-stem I and nut J. At the other extremity is received the hollow guide-plug F and the rod E, encircled by a spiral spring, G.

E is the connecting-rod operating the piston, extending from the interior of the piston-rod to the interior of the cab, where it terminates, and is secured by any well-known device, which is released by the engineer and thrust forward whenever he wishes to discharge the oil from the cylinder.

F is the hollow guide-plug, screwed into the rear

end of the tubular piston-rod, which serves to guide the rod E, and prevents its withdrawal entirely by means of the stud on the end of the rod E, also confining the spiral spring G within the cavity D².

G is a spiral spring encircling the rod E, within the cavity D². It compensates for any accidental movement communicated to the rod E, by oscillation of the cab, within which the other end of the rod E is secured by any of the well-known devices.

H is the valve closing the outlet of the cylinder B, and operated by the piston C, nut J, and tubular rod D.

I, the valve-stem, retained within the cavity of the piston-rod D¹ by the nut J.

J, the nut on the valve-stem.

K, the piston-valve, which opens when the piston is withdrawn, and closes when thrust forward.

L L are the perforations through the face of the piston C, which permit the passage of the oil through them into the forward part of the cylinder B, when the valve K is open.

M M are headed screws or rivets, which keep in position the valve K.

N is the packing-box, screwed on to the cylinder-head W.

O is the packing around the piston-rod D.

P is the outlet-chamber, screwed on to the forward end of the cylinder B, and which receives the oil as forced from the cylinder B, and delivers it through an open port on each side Q Q, fig. 1, into the conducting-pipes R R.

Q Q are the open ports of the outlet-chamber P.

R R are the tubes or pipes which convey the oil from the outlet-chamber P down into the steam-chests on each side of the boiler.

S is the steam-jacket enclosing the cylinder B and its contents, and nearly covering the bottom of the reservoir A. Steam is admitted through the hollow plug T. The office of this device is to keep hot and at a uniform temperature the oil, tallow, or other lubricants contained within the reservoir A and cylinder B.

T is the hollow plug, screwed into the top of the boiler, and is connected to the jacket by the screw-coupling U. The amount of steam admitted through the plug may be regulated by valves.

U is the screw-coupling connecting the plug T and steam-jacket S.

V is the screw-cap, or stopper, closing the inlet of the reservoir A, and is removed for filling the same.

W is the cylinder-head.

Various methods of packing the piston may be employed. We have found the common metallic ring to answer the purpose better than others in use.

The prime object of this invention is economy in the

use of oil or other lubricants, when applied to locomotive-engine cylinders.

It will be seen from the explanation of our invention that the cylinders may be lubricated simultaneously, by either the engineer or fireman, without leaving their cab, by simply thrusting forward the connecting-rod E, which is accessible to them within the cab at all times.

Having thus described our invention,

We claim, and desire to secure by Letters Patent—

1. The arrangement of the reservoir A, the cylinder B, outlet-chamber P, and conducting-pipes R R, when constructed in the manner herein described.

2. The arrangement of the cylinders B, valve H, and cylinder-head W, when constructed as shown and described.

3. The tubular piston-rod, when constructed as described, with a partition, D, to regulate the movements of the valve H and connecting-rod E.

The above specification of our invention signed by us, this 30th day of January, A. D. 1869.

SIMON F. STANTON.
ORVILLE RIPLEY.
